UNITED STATES PATENT OFFICE.

VERNON B. SMITH, OF CHICAGO, ILLINOIS.

DESIGN FOR A PAPER BIRD PUZZLE.

Application filed June 7, 1928. Serial No. 27,034. Term of patent 7 years.

To all whom it may concern:

Be it known that I, VERNON B. SMITH, a citizen of the United States, residing at Chicago, in the county of Cook and State of Illinois, have invented a new, original and ornamental Design for a Paper Bird Puzzle, of which the following is a specification, reference being had to the accompanying drawings, forming a part thereof.

The figure of the drawings is a perspective of a paper bird puzzle, showing my new design.

I claim:

The ornamental design for a paper bird puzzle, as shown.

In testimony whereof I affix my signature.

VERNON B. SMITH.
